UNITED STATES PATENT OFFICE.

WILLIAM A. U. SELTZER, OF PHILADELPHIA, AND GEORGE U. SELTZER, OF EAST DOWNTON, PENNSYLVANIA.

CONTACT SHOE FOR THE THIRD RAIL OF ELECTRIC CARS.

Application filed November 25, 1922. Serial No. 603,168.

To all whom it may concern:

Be it known that we, WILLIAM A. U. SELTZER and GEORGE U. SELTZER, citizens of the United States, and residents, respectively, of Philadelphia, county of Philadelphia, and State of Pennsylvania, and of East Downingtown, county of Chester, and State of Pennsylvania, have invented certain new and useful Improvements in Contact Shoes for the Third Rail of Electric Cars, of which the following is a specification.

Our invention relates to improvements in contact shoes, which are carried by electric cars and adapted for electrical contact beneath the usual third rail, whereby electric current is supplied to the motors of these cars.

The usual type of contact shoe now almost universally employed merely includes a laterally projecting spring controlled plate member carried by the under frame of the cars, and adapted for sliding contact beneath the third rails. It is a well known fact that these sliding type contact shoes quickly become worn away, due of course, to their sliding contact with the third rail, and it very frequently happens that after these shoes are worn away to a certain degree, a complete contact between the shoe and rail is not always provided.

In view of the above, it is therefore, the primary object of this, the present invention, to provide an improved contact shoe, wherein the same is provided with a relatively large and side roller member suitably journaled in ball bearings carried by the shoe, the said roller engaging beneath or upon the third rail, which construction will adequately overcome the above mentioned objections.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:

Figure 1 is a top plan view of my improved shoe per se, the same being shown

as pivotally connected to the usual shoe carrying arm of the electric car.

Figure 2— is a side elevational view of the device shown in Figure 1.

Figure 3— is a longitudinal cross sectional view of the shoe per se, the roller member being shown in elevation.

Figure 4— is a transverse sectional view upon the line 4—4 of Figure 1, and looking in the direction of the arrows.

Figure 5— is a fragmentary end elevational view of the shoe with the bearing block removed therefrom.

Figure 6— is a bottom plan view of the shoe per se.

Figure 7— is a transverse cross sectional view upon the line 7—7 of Figure 1, and

Figure 8— is a bottom plan view of one of the bearing blocks carried by the shoe, for maintaining the roller bearings in proper position upon the shoe.

With particular reference to the drawings, our device includes the provision of a substantially rectangular shaped metallic plate 1, having an annular shaped head 2 formed at the inner end thereof. The head 2 of the plate 1 is adapted to be pivotally connected to the usual supporting arm 3, which supporting arm carries or has formed thereon a central block 4, which is provided with a vertical bore for the reception of a bolt 5.

This bolt is headed at its lower end as at 6, and is adapted to engage through a bore 7 at the central forward portion within the head 2 of the plate 1. As shown, the bore 7 within the head 2 is enlarged at its upper end, and as more clearly shown in Figure 2, the said bolt 5 engages through this bore 7, the head 6 thereof engaging the lower surface of the said plate 1. Engaging over the upper end of this bolt 5 is a relatively strong coiled spring 6 engaging at its lower end upon the block 4 of the arm 3 and retained upon the bolt by a washer 8 and nut 9.

The arm 3, the headed bolt 5, spring 6 and block 4 formed upon this arm 3 are all elements, which are now found in the conventional type third rail contact shoe, and this structure is merely adapted for normally maintaining the shoe 1 in close contact with the surface of the third rail. It is therefore to be understood that these elements of construction are not claimed by me as a portion of our invention.

The outer end of the plate 1 is reduced as at 11 so as to provide shoulders 12 at each side of the plate. Further, this plate 1 is transversely channeled as at 13, adjacent the inner side of the cut out portion or opening 10. Centrally beneath the reduced end 11 and channel 13 of the plate, the same is formed with roller bearing receiving sockets 14, the said portions of the plate 1 being enlarged as at 15 for this purpose. Positioned within the sockets 14 of the enlargements 15 of the plate 1 are any desired form of roller bearing 16, and adapted to be received within these roller bearings 16 are the pintle ends 17 of a relatively enlarged roller 17', this roller being of such dimensions as to have the surface thereof to project above and beneath the top and bottom surfaces of the plate.

As a means for retaining the said bearings 16 within the enlargements 15 of the plate, there is provided transversely extending plates 18 positioned upon the reduced end 11 of the plate 12, and within the channel 13 thereof, respectively. As more clearly shown in Figure 8, these plates 18 are also centrally enlarged as at 19, which enlargements are provided with a suitable channel or groove 20 for receiving the upper end of the said roller bearings 16. These transverse members 18 are secured to the plate by suitable bolt connections 21.

The longitudinal sides of the opening 10 within the plate 1, are suitably concaved as at 22, more clearly shown in Figure 4. These concaved surfaces of the longitudinal sides of the opening 10 within the plate allows for a free rotary movement of the roller 17' within the said opening. Further, the plate 10 is provided at a point between the roller 17' and head 2 with a pair of current take-off bolts or plugs 23.

In view of the above description, it will at once be apparent, that we have provided

an improved form of third rail contact shoe 45 for electric cars wherein there is little, if any liability of the shoe to become so worn as to impair the proper operating efficiency thereof, and while we have herein shown and described the preferred embodiment of the invention, it is nevertheless to be understood that minor changes may be made when desired without departing from the spirit and scope of the invention as claimed.

What we claim as new is:—

1. In a device of the class described, a substantially rectangular shaped plate member having a head formed upon the inner end thereof, and adapted for pivotal connection to the usual plate carrying arm of an electric car, said plate member having a relatively large opening formed therein and adapted for the reception of a roller member suitably journaled within said plate.

2. In a device of the class described, a substantially rectangular shaped plate member adapted for pivotal connection to the usual plate carrying arm of an electric car, a roller positioned within an enlarged opening of the plate member and having pintles at the opposite ends thereof for free rotary movement within bearings carried by said plate member.

3. In a device of the class described, a plate member adapted for pivotal connection to the usual plate carrying arm of an electric car and having a central square shaped opening therein, a roller positioned within the opening and having pintles at the opposite ends thereof, bearings positioned in sockets formed at opposite ends of the central opening of the plate, and adapted for the reception of said pintles, and means for securing the bearings within the sockets.

In testimony whereof, we affix our signatures.

WILLIAM A. U. SELTZER.
GEORGE U. SELTZER.
